G. O. FALES

VEHICLE DIRECTION SIGNAL

Filed Feb. 20, 1923

UNITED STATES PATENT OFFICE.

GEORGE O. FALES, OF OMAHA, NEBRASKA.

VEHICLE DIRECTION SIGNAL.

Application filed February 20, 1923. Serial No. 620,128.

To all whom it may concern:

Be it known that GEORGE O. FALES, a citizen of the United States, residing at Omaha, in the county of Douglas and State of 5 Nebraska, has invented certain new and useful Improvements in Vehicle Direction Signals, of which the following is a specification, reference being had therein to the accompanying drawings.

10 The invention relates to vehicle direction indicators, and has for its object to provide a device of this character comprising a horizontally disposed shaft extending through the cowl of an automobile, and having 15 its outer end provided with a signalling arm adapted to be moved to various positions in a transverse vertical plane for signalling approaching vehicles as to the contemplated turn of the operator. Also to 20 provide spring means for normally maintaining the arm in inoperative position and foot controlled means for moving the arm to opposite positions.

A further object is to form the arm from 25 two sections having registering grooves for the reception of conductor wires leading to a chamber at the outer ends of the member in which an electric lamp is disposed, said chamber having its outer sides closed by 30 transparent members.

With the above and other objects in view the invention resides in the combination and arrangement of parts as hereinafter set forth, shown in the drawing, described and 35 claimed, it being understood that changes in the precise embodiment of the invention may be made within the scope of what is claimed without departing from the spirit of the invention.

40 In the drawing:—

Figure 1 is a perspective view of a portion of a conventional form of automobile, showing the signalling device applied thereto.

Figure 2 is a vertical sectional view 45 through a portion of the automobile and the signalling device.

Figure 3 is a rear view of the signalling device.

Figure 4 is a perspective view of one of 50 the signalling arm members.

Referring to the drawing, the numeral 1 designates a cowl of a conventional form of automobile, and 2 a horizontally disposed shaft extending through the cowl. The 55 shaft 2 is rotatably mounted in bearings 3

of plates 4 and 5, secured to the rear and forward sides of the cowl 1. Surrounding the shaft 2 is a coiled spring 6, one end of which is anchored to the shaft at 7 and the other end anchored to the plate 5 at 8, therefore it will be seen that the coiled spring 5 will return the shaft to normal position after each operation. The outer end 9 of the shaft is rectangular shaped and has disposed thereon a signalling arm 10. The arm 10 is formed from registering members 11, which are provided with rectangularly shaped apertures 12 for the reception of the rectangular shaped portion 9 of the shaft. It will be seen that the sections 11 will be held in registration with each other, and in close engagement when the nut 13 is threaded on the outer end of the shaft. Each section 11 is provided with a longitudinally extending groove 14, which grooves register with each other when the sections are brought together and form a longitudinally extending aperture for the reception of conductor wires 15, one of which leads to a contact member 15^a and the other is grounded at 15^b to the plate 5. The outer ends of the grooves 14 terminate in semi-circular shaped recesses 15 for the reception of the socket 16 of an electric lamp 17, thereby holding the lamp and socket against movement. The arm sections 11 are provided with registering openings 18, in which the lamp 17 is disposed, and the openings 18 are closed by transparent members 19. By providing the electric lamp 17, it is obvious that the signalling device may be used for night or day signalling.

The rear end of the shaft 2 is provided with an arm 20, which is adapted to be moved in the direction of the arrow *a* for 95 moving the signalling arm 10 in various positions during a signalling operation. Secured to the outer end of the arm 20 is a rod 21, which rod extends downwardly, and has its lower end connected at 23 to the free 100 end of a foot pedal 24, which pedal is pivotally mounted at 25. It will be seen that the operator may move the arm 10 to any angular position by simply depressing the foot pedal 24, and by providing a foot pedal 105 it will not be necessary for the operator to remove his hands from the steering wheel. The arm 20 is provided with a contact arm 20^a, which when moved during a signalling operation contacts with the contact member 110

15^a, closes the circuit and allows the lamp 17 to be lighted by the battery 26.

From the above it will be seen that a foot operated signalling device is provided for 5 automobiles, which device is simple in construction and one wherein, when the operator removes his foot from the pedal, spring means will return the signalling device to normal inoperative position.

10 It will also be seen that the signalling arm is formed from a plurality of sections, and that the sections are held in registration with each other by the rectangular shaped portion 9 of the shaft 2, which passes 15 through registering rectangular shaped apertures in the sections.

The invention having been set forth what is claimed as new and useful is:—

1. The combination with the cowl of an 20 automobile, of a signalling device carried thereby, said signalling device comprising a horizontally disposed shaft extending through an enlarged aperture in the cowl, plates secured to the opposite sides of the 25 cowl, and in bearings of which the shaft is rotatably mounted, a coiled spring surrounding the shaft and having one of its ends anchored to the shaft and its other end

to one of the plates, said coiled spring extending through the aperture in the cowl, a 30 signalling arm carried by the outer end of shaft, an arm carried by the inner end of the shaft, a depressable foot lever, and cable connections between the foot lever and the arm carried by the inner end of the shaft. 35

2. The combination with a vehicle direction signal, said signal comprising a rotatable shaft, spring means for returning said shaft to normal position after an operation, of a signalling arm carried thereby, said 40 arm comprising registering sections, the outer end of the shaft being rectangular shaped, and extending through registering rectangular shaped apertures in the sections of the arm, registering grooves carried by 45 the inner faces of the arm section, said registering grooves terminating in segmentally shaped recesses for the reception of an electric lamp socket, an electric lamp disposed in registering chambers of the arm sections, the outer sides of said chambers of the 50 arm sections being closed by transparent members.

In testimony whereof I hereunto affix my signature.

GEORGE O. FALES.
